Primary Examiner — Rosemary K Tarcza*Assistant Examiner* — Yolanda Robinson(74) *Attorney, Agent, or Firm* — Westerman, Hattori, Daniels & Adrian, LLP(57) **CLAIM**

The ornamental design for a steering pad for automobile, as shown and described.

DESCRIPTION

FIG. 1 is a perspective view from the front side of a steering pad for automobile.

FIG. 2 is a front elevation view thereof.

FIG. 3 is a top plan view thereof.

FIG. 4 is a bottom plan view thereof; and,

FIG. 5 is a right side elevation view thereof.

The broken lines shown in the drawings illustrate portions of the steering pad for automobile that form no part of the claimed design.
